VARIABLE-FLOW PUMPS OF THE DRUM
PISTON TYPE

Georges Garnier, Asnières, France, assignor to Air-Equipement, Asnières, France, a French company

Filed Mar. 5, 1958, Ser. No. 719,329

Claims priority, application France Mar. 8, 1957
5 Claims. (Cl. 103—162)

The object of the present invention is to provide improvements in variable-flow pumps of the drum piston type i.e. having pistons sliding in bores provided in a drum, or rotor, pumps in which the stroke of the pistons in the rotor depends on the position of a cam or swash-plate tiltable about an axis orthogonal to the axis of the rotor.

One of these improvements concerns the manner of mounting the rotor. It is known that, to obtain correct pump operation, it is essential that the rotor remains applied constantly against the distribution surface, the slightest gap or separation between the rotor and distribution surface creating considerable leakage.

It has been discovered that, to satisfy this condition, the rotor must be carried by at least one main bearing disposed in a well-defined region in the vicinity of the pivot axis of the cam, and that, if other bearings are provided outside said region, these bearings must have greater play than that of the main bearing or bearings.

The region in which the main bearing or bearings are located is determined mathematically by the condition that the resultant of the forces exerted on the rotor, apart from the reaction of the distribution surface be directed toward said distribution surface and fall within the surface of contact of the rotor and the said distribution surface.

In a particular embodiment, the rotor is carried by a shaft which extends therethrough and is rigidly fixed to the housing, the bearing, or bearings, being disposed in the aforementioned region.

This arrangement is advantageous in that the presence of the cam plate, the piston shoes and the support plate, makes it practically impossible to provide a bearing outside the rotor in the defined region mentioned hereinbefore.

This arrangement also enables the rotor to be driven by a ring gear machined directly on the rotor and meshing with a gear rigid with the driving shaft of the pump, since only the arrangement of a central shaft permits providing a rotor bearing in a plane perpendicular to the rotor axis and containing said ring gear.

In this case, the invention also provides an arrangement whereby the meshing of the rotor ring gear is such that the delivery passageway of the pump is located in the plane of the meshing and on the side of the axis of the rotor opposed to that of said meshing.

According to another improvement to the centering of the pump body or rotor in the housing, there is provided, in addition to a main bearing on the pump body itself, a second bearing carried by the housing and in which is journaled the cylindrical end of a shaft fitted in the pump body, for example by a conical portion, and fixed in position by a nut.

Another improvement is in the pivotal mounting of the tiltable cam or swash plate and provides, in addition to the usual pivot pin, abutment means which exerts on the cam an action balancing the thrust exerted on the cam by the pump pistons, this abutment means being in contact with the cam through the medium of a part-cylindrical face, the axis of the cylinder coinciding with the pivot axis of the cam.

In one embodiment, this abutment means is constituted by fixed parts rigid with the housing or machined in one

2

piece with the latter. In a modification, this abutment means is constituted by a balancing piston disposed in a bore in the housing and constantly applied against the rear face of the cam by the delivery pressure in a region defined in suitable manner for substantially balancing the thrust exerted on the cam by the pump pistons. Owing to this fixed abutment member, or to this balancing piston, the pivot pin merely maintains the cam in position and is subjected to but a small force.

In another improvement, the plate which applies the piston shoes against the forward face of the cam is positively driven in rotation by the rotor so as notably to reduce friction. This drive could be obtained, on the one hand, by providing a suitable connecting means, for example of universal joint type, between the support plate for the shoes and the sliding return member which is axially disposed in the rotor and is subjected to the action of a spring and, on the other hand, by positively driving this axial return member through the medium of the rotor.

In a particular embodiment of this connecting means, the latter is formed by a thin member comprising two lugs disposed in a recess in the support plate for the shoes and two lugs disposed in a recess disposed in the axial return member orthogonal to the other recess.

The positive driving in rotation of the return member may be ensured by a lug forming a key or by a sliding connecting between the return member and the end of the shaft journaled in the auxiliary bearing of the pump body, which has, for example, flat-faced portion and is slidably mounted in an aperture having a corresponding shape formed in an axial extension of the return member.

Another improvement relates to the piston shoes. The spherical head of the piston is generally set in the shoe and the latter bears on the cam by a flat part. It is very advantageous to reduce the coefficient of friction of the shoe on the cam so as to improve the efficiency and prolong the life of the pump.

For this purpose, it has already been proposed notably to make the cam plate of graphite or to provide electrolytically a deposit or layer of metal on the shoe having a good coefficient of friction (cadmium, indium or silver, for example). But these solutions have disadvantages. In the first case, the graphite cannot support high mechanical stresses and the cam plate of graphite must incorporate a rigid reinforcement, for example of steel. The result is a rather space-consuming structure which is heterogeneous and might be rather fragile. In the second case, the electrolytic coatings on the shoe are thin and it is difficult to be sure of their adherence, and numerous difficulties have arisen due to irregular deposits which flake off.

According to the invention, the shoes are provided with an element comprising at least one flat face and composed of a metal having a good coefficient of friction, for example silver, this element being disposed in the shoe in such manner that the flat face protrudes from the shoe and ensures that the shoe bears against the cam plate only through the medium of this flat face. This element could be set in the shoe or could be simply maintained in position by the force exerted by the piston on the cam.

In a particular embodiment of said element, the latter is in the form of a thin plate lodged in a shallow recess in the shoe.

In another embodiment, said element protrudes from the shoe not only on the side adjacent the cam but also on the side adjacent the head of the piston and the recess formed in the shoe is such that the spherical head of the piston is retained merely by the edges of the shoe and bears against the inner protruding face of said sliding element.

It can be seen that after wear of the sliding plate or element of the invention, it is easily changed by dismantling the pump, whereas wear of the electrolytic deposits would require changing the entire shoe, that is, would require detaching the spherical end of the piston.

Further features and advantages of the invention will be apparent from the ensuing description, with reference to the accompanying drawings, of variable-flow drum piston pumps incorporating the improvements of the invention.

In the drawings:

FIG. 1 is an axial sectional view of a pump having two outer bearings;

FIG. 2 is a view partly in section and partly in plan view taken along line II—II of FIG. 1;

FIG. 3 is a sectional view taken along line III—III of FIG. 1;

FIG. 4 is an axial sectional view of a modification of a detail of the pump shown in FIG. 1;

FIG. 5 is a partial axial sectional view of a modification of the pump shown in FIGS. 1 to 3 in which the balancing piston of the cam is replaced by a fixed abutment member rigid with the housing of the pump;

FIG. 6 is a sectional view taken along line VI—VI of FIG. 5;

FIG. 7 is an axial sectional view of a pump having inner bearings and a central shaft;

FIG. 7a is a diagrammatic plan view of the pump of FIG. 7 showing the forces acting on the barrel and the resultant force thereof;

FIG. 7b is a diagrammatic end view corresponding to FIG. 7a;

FIG. 8 is an axial sectional view of a detail of the mounting of the piston shoes; and

FIG. 9 is an axial sectional view of a modification of the mounting of a piston shoe.

In the embodiment shown in FIGS. 1-3, the pump comprises a steel pump body or rotor 1 journalled in the housing 2 through the medium of a bearing 3 composed, for example, of graphite. The pump body, or rotor, is driven in rotation by a shaft 4 through the medium of a gear 5 meshing with a ring gear 6 whose teeth are machined directly in the rotor 1.

The position of bearing 3 is determined by calculation as will be explained hereinafter with reference to embodiment of FIG. 7, in order that the resultant of the forces applied on rotor 1 falls within the surface of contact of the distribution member and the rotor 1. Said calculation shows here that said bearing 3 ought to be located between the transverse plane containing the pivot axis 20 of cam or swash plate 15 and said distribution member, in the immediate vicinity of said transverse plane.

In order to improve the centering of the rotor 1 in the housing 2, there is provided an additional bearing 7 carried by the housing and in which is journalled the cylindrical extension 8 of a shaft 9 which is fitted by a tapered portion 10 in the rotor 1 and held fast by a nut 11.

The pump comprises pistons 12 which slide in bores 13 formed in the rotor, each of these bores being provided with a liner 14, for example composed of silver, to reduce friction.

The pump delivery or discharge flow is controlled by a tiltable cam or swash plate 15 against the forward face of which the heads 16 of the pistons 12 bear through the medium of their shoes 17 and of a bearing member, or plate, 18.

The cam 15 carries two ears 19, 19' provided with apertures in which is journalled a pivot pin 20 carried by a support 21 rigid with the housing. This pivot pin is adapted merely to maintain the cam 15 in position and is only subjected to a small force owing to the provision of balancing means which will now be described.

Provided in a bore 22 suitably disposed in the housing, is a piston 23 which is constantly applied by its forward face against the corresponding rear face 24 of the cam

under the effect of the delivery pressure of the pump prevailing in the chamber 22 at the rear of the piston. The forward face of the piston and the corresponding part 24 of the cam have a part-cylindrical shape, the axis of the cylinder coinciding with the axis of the pivot pin 20 thereby permitting tilting of the cam.

By means of this arrangement, the cam 15 is constantly balanced by the action of the piston 23 whose position is precisely determined so that its thrust balances substantially the resultant of the thrusts exerted on the cam by the pump pistons. The inclination or tilt of the cam is controlled by a small piston 25 actuated hydraulically and the return of the cam is ensured by the action of a piston 26 the rear of which is continuously subjected to the delivery pressure.

In order to reduce friction, the support plate 18 of the shoes 17 of the pistons 16 is driven positively in rotation by means of a universal joint formed by a thin member 27 carrying upstanding lugs. Two of these lugs 28 are disposed in a slot 29 in the plate 18 and two other lugs 30 are disposed in a groove 30 orthogonal to the slot 29 and provided in a slide member 31 which is slideable in an axial bore 32 in the rotor and is biased toward the cam 15 by the effect of a return spring 33. The slide 31 is itself positively driven in rotation by the pump body owing to the provision of keying on the shaft 9. This keying is formed, in the presently-described embodiment, by the flat-faced end 35 of the shaft 9 which is engaged in the swaged portion 36 of the slide 31.

In the modification shown in FIG. 4, the slide 31 is driven directly by the pump body through the medium of a pin 37 or the like forming a key.

In the embodiment shown in FIGS. 5 and 6, the balancing of the cam 15 is ensured by the abutment of the latter against protruding portions or bosses 38, 38' provided on the housing 2, the zone of contact between the cam 15 and the portions 38, 38' being a part-cylindrical surface 39 the axis of the cylinder coinciding with the pivot axis of the cam, namely, the axis of the pin 20. The resultant of the thrusts exerted on the cam by the pump pistons is therefore in this embodiment balanced by the reaction of the housing on the cam.

In the embodiment shown in FIG. 7, the pump is mounted on a central shaft. The elements corresponding to those of the pumps shown in FIGS. 1-3 or 5 and 6 carry the same reference characters.

In this embodiment, the rotor 1 is mounted on a central shaft 40 rigidly fixed in the housing 2 and extending through the pump. The rotor 1 is journalled on the shaft 40 through the medium of a main anti-friction or roller bearing 41 and a secondary anti-friction or roller bearing 42, the play in the latter being greater than that in the bearing 41. The rotor 1 is driven by the shaft 4 through the medium of the gear 5 meshed with the ring gear 6 directly machined in the rotor.

The main bearing 41 is situated at the end of the rotor adjacent the control cam 15 in a region which is determined by calculation in such manner that the resultant of the forces applied on the rotor 1 is directed toward the distribution surface 43 and falls within the surface of contact of this surface and the adjoining face of the rotor 1, in order that, owing to this arrangement, the rotor 1 remains constantly applied against the surface 43 during pump operation and the presence of the secondary bearing 42 in the vicinity of the face 43 also ensures correct application when the pump is inoperative.

The above calculation is made in considering (see FIGS. 7a and 7b) the rotor 1 and pistons 12, as a whole, submitted to the following forces:

- 70 (1) Resultant F_p of the forces exerted by cam 15 on piston shoes 17;
- (2) Driving force (or couple of forces) F_M ;
- (3) Hydraulic force F_H exerted on rotor 1 by the fluid bottled up between said rotor and the distribution transverse wall 43;

(4) Resilient force F_R exerted by the resilient member (33, see FIG. 1), if any, to apply the piston heads 16 against cam 15;

(5) Reaction R_P of bearing 41, the moment of which is a function of the distance x between said bearing 41 and said transverse wall 43;

(6) Reaction force R_G of the transverse wall 43 on rotor 1.

It is the above reaction force R_G which is the subject of the calculation and: $R_G = -\epsilon(F_P, F_M, F_H, F_R, R_P)$.

For the calculation, the point of origin of the coordinates axes is chosen at the center of the distributor transverse wall 43; the axes ox , oy are in the plane of said wall 43, oy being directed towards the delivery port 45.

The magnitude and point of application of the different forces are determined by the following considerations:

(1) Resultant F_P of the forces exerted by the cam 15 on the piston shoes 17 is perpendicular to said cam (providing there is no substantial friction); its point of application is at the center of gravity of the half-circle having a radius b equal to the boring radius of the piston bores, and its component parallel to the axis oz balances the force F generated by the delivery pressure of the pump applied to half of the number of pistons 12.

(2) Driving force F_M has its point of application at the meshing point of driving gear 5 with the toothed ring 6, its direction is defined by the pressure angle of the gear teeth, and its magnitude is determined by the fact that the moment, relative to axis oz , of its component parallel to ox , balances the moment, relative to the same axis, of F_P .

When the rotor is driven through an axial drive, the driving shaft applies to the rotor a pure torque.

(3) The hydraulic force F_H applied to the rotor is parallel to oz and its point of application is at the center of gravity of the half-circle having a radius c equal to the mean radius of the delivery and induction ports 45, 46, its magnitude is equal to the product of F and a factor which depends on the balancing coefficient of the pump.

(4) Force F_R , in the case of an axial spring 33 (see FIG. 1) is applied at the origin of the coordinates axes and is parallel to oz .

(5) The reaction force R_P of the bearing 41 is perpendicular to oz and balances all components of the aforementioned forces which are perpendicular to oz .

(6) And the reaction force R_G of the transverse wall 43 on rotor 1 is parallel to oz ; its magnitude is equal to: $F_H - F - F_R$ and its point of application in the plane of transverse wall 43 is determined by writing that the moments of said force R_G relative to axes ox and oy are, respectively, equal to the sums of moments of aforementioned forces relative to the corresponding axes.

The coordinates of said point of application of R_G being thus calculated, the conditions for said point to be inside the circle having the radius r of the distributor transverse member 43 give the limits between which is to be located the main bearing 41, to be sure that rotor 1 remains always correctly applied against said transverse wall 43 to provide a perfect working of the pump.

The secondary bearing 42 is in the same transverse plane perpendicular to the shaft 40 as the ring gear 6 which is obviously most advantageous and only possible with a rotor mounted on a central shaft.

The line of meshing between the gears 5 and 6 is in the same plane as the axis of the induction passageways 44 and delivery passageways 45 and on the side of the axis of the rotor opposed to that of the delivery passageway 45. The application of the rotor against the distribution surface 43 is thereby still further improved.

The cam 15 abuts, through the medium of a cylindrical boss formed thereon, against the parts 38 having corresponding shape of the housing 2 and can be tilted by a shaft 20 which is integral therewith and disposed in a corresponding bore in the housing. The tilting of the cam 20 is controlled by a control lever 46 which is fixed

on the end 47 of the shaft 20 and extends out of the housing through a suitable aperture.

In the embodiment shown in FIGS. 1 to 7, the spherical heads 16 of the pistons 12 are set into the shoes 17 and the latter bear on the cam 15 by their flat faces 47. In order to reduce friction, the shoe is covered on this face with a suitable electrolytic deposit or the cam is composed, for example, of graphite.

In the embodiment shown in FIG. 8, the shoe 17 comprises a recess 48 in which is disposed a thin friction plate 49 which protrudes from the face 47 of the shoe. Thus, the piston bears against the cam 15 solely through the medium of this plate 49 which is provided with an aperture 50 for the passage of lubricating oil. This plate is composed of a metal having a good coefficient of friction, for example silver, and is easily changed when worn out.

In the modification shown in FIG. 9, the friction plate is replaced by a substantially frusto-conical element 51 whose flat face 52, protruding from the face 57 of the shoe 47, bears against the cam 15. The inner part 53 of the element 51, disposed in an aperture of corresponding shape formed in the shoe, has a part-spherical concave shape and extends inwardly of the shoe. The recess in the shoe receiving the piston head has such shape that the piston head 16 is merely retained by the edges 54, it bearing solely against the concave part 53 of the element 51. Thus, friction both inside and outside the shoe only results in wear of the element 53 which is easily changed.

Although specific embodiments of the invention have been described, many modifications and changes may be made therein without departing from the scope of the invention as defined in the appended claims. Thus, the pistons need not be parallel with one another and the shaft journaled in the lateral bearing could be mounted in the rotor by means other than a tapered extension held in place by a nut.

What I claim is:

1. In a pump of the drum piston type comprising a housing having a transverse wall and provided with an induction passageway and a delivery passageway opening on said transverse wall of said housing, a rotor mounted for rotation about an axis in said housing and having a lateral face in contact with a corresponding surface of said transverse wall and bores opening on said lateral face, pistons disposed for reciprocation in said bores and having each a part-spherical head outside said rotor, a cam having a flat face cooperating with said heads of said pistons for controlling the movement of said pistons in said rotor, a shoe mounted on each of said heads of said pistons and having a flat face resting against the flat face of said cam, a retaining plate for biasing said shoe against said cam, a spring biased member axially and slidably mounted in said rotor, said spring biased member and said plate providing contacting surfaces between the spring biased member and the plate, said contacting surfaces providing grooves and projections fitting in said grooves for positively driving the plate via the spring biased member.

2. In a pump of the drum piston type comprising a housing having a transverse wall and provided with an induction passageway and a delivery passageway opening on said transverse wall of said housing, a rotor mounted for rotation about an axis in said housing and having a lateral face in contact with a corresponding surface of said transverse wall and bores opening on said lateral face, pistons disposed for reciprocation in said bores and having each a part-spherical head outside said rotor, a cam having a flat face cooperating with said heads of said pistons in said rotor, a shoe mounted on each of said heads of said pistons and having a flat face resting against said flat face of said cam, a retaining plate for applying said shoe against said cam and having a hemispherical portion, a spring biased member axially and slidably

mounted in said rotor but keyed in rotation with said rotor and having a hemispherical portion fitting with said hemispherical portion of said retaining plate for urging said plate and said shoes towards said cam, grooves on one of said corresponding hemispherical portions of said retaining plate and said spring biased members, and projections on the other of said hemispherical portions engaging with and cooperating with said grooves.

3. In a pump of the drum piston type comprising a housing having a transverse wall and provided with an induction passageway and a delivery passageway opening on said transverse wall of said housing for circulation of the fluid to be circulated by said pump, a rotor mounted for rotation about an axis in said housing and having a lateral face in contact with a corresponding surface of said transverse wall exerting on said rotor a reaction force substantially perpendicular to said lateral face and bores opening on said lateral face, pistons disposed for reciprocation in said bores and having each a head outside said rotor, a cam cooperating with said heads for controlling the movement of said pistons in said rotor comprising a support mounted for rocking movement about an axis extending at right angles to the axis of rotation of said rotor and exerting on said piston heads forces which have a resultant perpendicular to said cam, resilient means urging said pistons against said cam thereby exerting a force on said rotor, a toothed ring directly machined in the lateral face of said rotor, and a driving shaft having its axis parallel to the axis of rotation of said rotor, a gear carried by said driving shaft and meshing with said toothed ring for rotating said rotor and exerting on said rotor a driving force, a main bearing for supporting said rotor in said housing and exerting on said rotor a bearing reaction force substantially perpendicular to said axis of said rotor and forming with said resultant force exerted by said cam on said piston heads, said hydraulic force, said driving force, said force exerted by said resilient means and said reaction force exerted by said transverse wall on said rotor a system of forces having a zero resultant, said main bearing being located in a plane be-

5

tween the transverse plane containing the axis of rocking movement of said cam and said transverse wall at a distance from said transverse wall such as to have said reaction force exerted by said transverse wall on said rotor fall inside said corresponding surface of said transverse wall and be directed towards said rotor.

10

4. In a pump as in claim 3, further comprising a secondary bearing located substantially in the plane containing said toothed ring and supporting said rotor with a play exceeding the play of said main bearing.

15

5. In a pump as in claim 3, wherein said delivery passageway is located in the axial plane containing the line of mesh between said toothed ring and said gear on the side of the axis of the rotor opposed to that of said line of mesh.
